(57) **CLAIM**

The ornamental design for adapter for precision fluid dispenser tube, as shown and described.

DESCRIPTION

FIG. 1 is a front elevation view of an adapter for precision fluid dispenser tube, showing my new design, the rear view being identical thereto;

FIG. 2 is a right side elevation view thereof, the left side view being identical thereto;

FIG. 3 is a top plan view thereof;

FIG. 4 is a bottom plan view thereof;

FIG. 5 is a cross-sectional view thereof, taken in the direction of line 5-5 as seen in FIG. 2;

FIG. 6 is a perspective view thereof; and,

FIG. 7 is an alternate front view thereof, shown in use. The dot-dash broken line seen in the FIG. 5 drawing view represents the bounds of the claimed design; The broken line showing of the tube in FIG. 7 is included for the purpose of illustrating environment of the article, while all other broken lines are included for the purpose of illustrating portions of the adapter for precision fluid dispenser tube; the broken lines form no part of the claimed design.

1 Claim, 7 Drawing Sheets
